UNITED STATES PATENT OFFICE

116,341

DESIGN FOR A COUNTERBORE

Oscar C. Hedin, Minneapolis, Minn.

Application June 28, 1939, Serial No. 85,730

Term of patent 14 years

To all whom it may concern:

Be it known that I, Oscar C. Hedin, a citizen of the United States, residing at Minneapolis, county of Hennepin, and State of Minnesota, have invented a new, original, and ornamental Design for Counterbores, of which the following is a specification, reference being had to the accompanying drawing, forming part thereof.

In the drawing:

Figure 1 is an elevational view of a counterbore showing my new design.

Figure 2 is an elevation after the tool has been turned through an angle of about ninety degrees from that shown in Figure 1; and

Figure 3 is a top view of Figure 1.

I claim:

The ornamental design for a counterbore, as shown.

O. C. HEDIN.
